United States Patent Office.

CARL TIELENIUS, OF NEW YORK, N. Y.

Design No. 4,852, dated April 25, 1871.

DESIGN FOR A FAUCET-HOLDER.

The Schedule referred to in these Letters Patent and making part of the same.

To all whom it may concern:

Be it known that I, CARL TIELENIUS, of New York city, in the county and State of New York, have invented a new and original Design for a Faucet-Holder; and I do hereby declare that the following is a full, clear, and exact description thereof, which will enable others skilled in the art to make and use the same, reference being had to the accompanying photograph forming part of the specification.

The photograph represents a face view of my new design.

This invention relates to a new ornamental frame for holding the faucets from which liquors or perfumes are discharged.

The said frame is made in form of an ornamental lyre, with a head of Bacchus at the upper end, and three, more or less, upright rods in the middle.

The faucets are fitted into the lower ends of said rods.

In place of the said rods small vessels may be arranged within the frame.

I claim as my invention—

The design for a faucet-holder herein described.

CARL TIELENIUS.
